UNITED STATES PATENT OFFICE.

CARL AXEL LIND, OF MINNEAPOLIS, MINNESOTA.

SANDPAPERING MACHINE.

1,241,407.

Specification of Letters Patent. Patented Sept. 25, 1917.

Application filed February 3, 1916. Serial No. 75,947.

To all whom it may concern:

Be it known that I, CARL AXEL LIND, a subject of the King of Sweden, residing at Minneapolis, in the county of Hennepin 5 and State of Minnesota, have invented a new and useful Improvement in Sandpapering-Machines, of which the following is a specification.

The object of this invention is the production of a sand papering machine of simple and inexpensive construction. Heretofore much annoyance and expense has occurred by the abrasive material such as sand paper wearing and breaking, due to the 10 speed at which it travels, and the curve which it must follow when mounted upon a belt. My invention overcomes this objection by the production of a novel construction of belt, which will support the band 15 of sand papering material, and cause it to travel at suitable speed to produce the most efficient and effective results in smoothing plain surfaces of material.

To these ends my invention comprises the 20 features of construction and combination of parts hereinafter more particularly described and claimed.

In the drawing forming part of this specification, Figure 1 is a side elevation; 25 Fig. 2 is a section upon line X—X, Fig. 1; Fig. 3 is a plan of a detail of the belt; Fig. 4 is a section of a detail of the belt and its immediate coöperating parts; Fig. 5 is a perspective of one of the belt sections, 30 Fig. 6 is a cross section of one of the belt sections, Fig. 7 is a perspective of one of the links, and Fig. 8 is a perspective of one of the keys.

In the drawing, A is the main frame of 35 a machine, in which is mounted a horizontal vertically slidable table B consisting of a bed 2 carrying at its ends belt pulleys 3 and 4 on shafts 8 and 8'. A movable belt 5 passes around the belt pulleys being 40 driven thereby with its upper side movably mounted upon a series of antifriction rollers 6, which are journaled in said bed. The journal blocks such as 7 in which the shaft 8 is journaled is slidably mounted in an end 45 of the bed 2 and held adjusted by tightening bolts 9. By the adjustment of these bolts the tension of the carrying belt 5 can be regulated. The bed with the parts carried thereby is raised and lowered by screws 50 of the bed 2 and held adjusted by tightening bolts 9. By the adjustment of these bolts the tension of the carrying belt 5 can be regulated. The bed with the parts carried thereby is raised and lowered by screws 55 10, and a system of bevel pinions and shafts

11 and 12, one of said shafts being provided with a hand wheel 13, by the turning of which the height of the table is adjusted and regulated. The belt 5 is driven at suitable speed to feed the material to be smoothed 60 into the machine by a drive pulley 13, shaft 12, pulley 39, belt 40, pulley 41, pulley 41', cross belt 42 and pulley 43, the latter being mounted on the shaft 8' which carries the pulley 4 and journaled in the table 2. 65 A link 44 which is pivoted about shaft 12 has a yoke 44' on its free end in which the pulleys 41 and 41' are journaled and compensates for the adjustment of the table vertically. 70

Mounted upon the upper portion of the frame A is a sand papering device C, consisting of the following parts. 15 and 16 are pairs of pulleys respectively mounted and carried by shafts 17 and 18, the shafts 75 17 being journaled in pillar blocks 19, which are integral with the frame A and the shaft 18 being journaled in movable pillar blocks 20 which are slidably mounted in said frame and held in adjusted position by 80 the tightening bolts 21 by the adjustment of which the belt D passing around the pulleys 15 and 16 can be regulated in tension. The belt D consists of a series of sections of the same size and shape resembling bars 85 such as 21 flexibly united by links 22. Each of said bars is made in two sections, the upper section 23 thereof being secured to the lower section 24 by screws 25. The two sections 23 and 24 are formed with a series of 90 evenly spaced cavities 26, openings thereto extending from each of the two opposite sides 27 and 28 of the bar. The upper surface of each cavity is formed with a downwardly projecting shoulder 29 while 95 the lower surface below said shoulder is slanted down in a gentle curve 30 toward the adjacent side of the bar. The cavities 26 of each bar are arranged with their shoulders and curved surfaces referred to 100 alternating, that is the shoulder and curved surface of one cavity faces outwardly toward one side of the bar, while the next adjacent cavity in said bar has its shoulder and curved surface facing toward the opposite side of said bar. The adjacent bars of 105 the belt have their shoulders and coöperating curved surfaces corresponding, so that a link such as 22 engaging one shoulder in one of the cavities will extend forwardly 110

over the curved surface 30 and engage a shoulder in the corresponding cavity of the adjacent bar. Thus the sections of the belt are freely united together. Each of the 5 links 22 is formed with a hook member such as 31 at each of its opposite extremities. The inner surface of each hook being curved inwardly in the form of a depression 32 in the lap of which a key 33 is loosely held 10 back in the shoulder 29, there being a key held by each hook member back of the corresponding shoulders of a pair of bars of the belt. This construction produces a flexible coupling between the sections of the 15 belt, permitting the belt to travel evenly around the curved surfaces of the pulleys 15 and 16. The adjacent sides 27 and 28 of each pair of bars on the belt diverge inwardly apart, thus allowing the sections of 20 the belt to conform freely with the outer surfaces of the pulleys 15 and 16 as the belt travels around them. When desired the 25 couplings can be suspended in the openings of the bars of the belt by screws 46 movably passing through slots 47 in the bars into one end of each coupling. The upper and lower sides of the belt are held taut by said 30 pulleys and carry the abrasive belt 34 made out of sand paper or other suitable material without stretching it unevenly any time during its course over the flat sides and end 35 curved surfaces of the belt. The outer surfaces 35 of the sections of the belt are also curved, so that the sand papering belt will conform evenly and smoothly over the main belt as it travels around the curved ends without uneven stretching and becoming 40 broken. The curves 30 it will be noted permit the lower surfaces of the links 22 to work freely in the cavities of the bars. The body of the sand papering belt may be 45 made out of any suitable flexible material from which belts of this character are usually constructed, the belt being made of endless construction by uniting its ends together or otherwise, and then being placed over the pulleys 15 and 16 and tightened. Power is transmitted to the supporting belt 50 D by means of a pulley 35, belt 36 and pulley 37, the pulley 35 being mounted upon the shaft 18 and the pulley 37 on the shaft 12. The lower side of the sand papering belt lies substantially horizontal and at suitable regulated height above the bed 2 and 55 substantially parallel with the upper side of the carrier belt 5. In use the height of the bed 2 and its coöperating parts is regulated by turning the handle 18' and power applied to the machine by the main drive pulley 18. The material which is to have its 60 surface smoothed is passed into the bite of the lower side of the sand paper belt 34, and the upper side of the carrier belt on the table 2, the parts of the machine being operated in the direction of the arrows indi-

cated in the drawings. The sand paper belt and the feed belt are driven in the same direction, said feed belt being driven at slower speed than the speed imparted to the sand paper belt. As the material is passed inwardly between the adjacent sides of the sand papering belt and the carrier belt, the surface of said material is smoothed evenly without unduly wearing the sand papering material due to its contact with the body of the belt D. 70

In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following claims. 75

Having described my invention what I claim as new and desire to protect by Letters Patent is:

1. A sand papering machine, comprising, in combination, a main frame, a table adjustable in elevation upon said frame, a feed belt having a flat side traveling over the surface of said table, a supporting belt having a flat side traveling adjacent to the flat side of said feed belt and an endless band of abrasive material carried by said supporting belt, said supporting belt consisting of a series of transverse bars linked freely together, each bar having a convex outer surface and inwardly tapering clearance sides, whereby the abrasive belt is carried without any uneven stretching. 90

2. A sand papering machine, comprising, in combination, a main frame, a table adjustably supported in elevation upon said frame, a feed belt having a flat side traveling over the surface of said table, a series of antifriction rollers on said table over which the flat side of said belt travels, a supporting belt having a flat side traveling adjacent to the flat side of said feed belt and an endless band of abrasive material carried by said supporting belt, said supporting belt consisting of a series of transverse bars linked freely together, each bar having clearance surfaces, whereby the abrasive belt is carried without any uneven stretching. 100

3. A sand papering machine, comprising, in combination, a main frame, a table adjustably supported in elevation upon said frame, a feed belt movably mounted upon said table and having a flat side traveling over the surface of said table, means operative from a single hand device for raising and lowering said table, a supporting belt having a flat side adjacent to the flat side of said feed belt, an endless band of abrasive material 115

130

carried by said supporting belt, means for driving said belts with their adjacent sides in the same direction and at different speeds, said supporting belt consisting of a series of transverse bars freely linked together, each bar having a convex outer surface and each pair of adjacent bars having adjacent side

clearance surfaces, whereby the abrasive belt is carried by said supporting belt without any uneven stretching. 10

In testimony whereof, I have signed my name to this specification.

CARL AXEL LIND.
